UNITED STATES PATENT OFFICE

100,665

DESIGN FOR A BRACELET

Henry P. Kelley, Coral Gables, Fla.

Application May 25 1936, Serial No. 62,813

Term of patent 7 years

To all whom it may concern:

Be it known that I, Henry P. Kelley, a citizen of the United States, residing at Coral Gables, in the county of Dade, and State of Florida, have invented a new, original, and ornamental Design for a Bracelet, of which the following is a specification, reference being had to the accompanying drawing, forming part thereof.

The figure is a plan view of a bracelet, showing my new design.

The characteristic feature of my design resides in the arrangement of flag pendants on a bracelet chain in the manner shown.

I claim:

The ornamental design for a bracelet, as shown and described.

HENRY P. KELLEY.
